COOLING AND DISPLAY STAND

Murray M. Fibus, Youngstown, Ohio

Application January 9, 1943, Serial No. 471,898

2 Claims. (Cl. 211—74)

This invention relates to a cooling and display stand for bottled goods.

The principal object of the invention is the provision of an ornamental display stand adapted to hold and display a plurality of bottled liquors.

A further object of the invention is the provision of a display stand for bottled liquors provided with means for cooling the bottles and their contents.

A further object of the invention is the provision of a cooling and display stand wherein means are incorporated for illuminating bottles displayed therein.

A still further object of the invention is the provision of a cooling and display stand for bottled goods adapted to cool the same by directing a cooling agent thereagainst.

The cooling and display stand for bottled goods shown and described herein has been devised to provide an attractive article for positioning upon the back bar of an establishment dealing in bottled goods, particularly where such goods are served by the drink from the original bottles. It is well known that various liquids commonly used as beverages are more palatable when cool and it is, therefore, one of the primary objects of this invention to provide for the cooling of bottled beverages such as liquors. It is well known that the back bar of establishments where the device is used comprises the display area of the merchandise for sale, and the device, therefore, has been formed as a display stand so that the various bottles of liquor positioned therein are attractively displayed at a location convenient to the bar-tender and means have been incorporated in the device of the invention for causing the illumination of the various bottles displayed so that the bottles and the labels thereon may be readily seen and identified.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

Figure 1 is a front elevation of the cooling and display stand for bottled goods.

Figure 2 is a top plan view of the device.

Figure 3 is an enlarged cross sectional elevation taken as on lines 3—3 of Figure 1.

Figure 4 is a cross sectional elevation of a bot-

tle illuminating and holding member comprising a part of the device illustrated in Figures 1 and 2.

Figure 5 is a cross sectional elevation of a bottle illuminating and positioning member comprising a modified structure used in place of the device illustrated in Figure 4.

By referring to the drawing and Figures 1, 2 and 3 in particular, it will be observed that an attractive and convenient cooling and display stand for bottled beverages has been devised. The device itself comprises a tiered body section 10, the lower tier of which is indicated by the numeral 10A and the upper tier of which is indicated by the numeral 10B. Each of the tiers 10 and 10A are provided with a plurality of openings and the tier 10B is provided with a single opening. It will be observed that the uppermost face of the tier 10A is indicated by the numeral 11 and that the same is at an elevation above the lowermost or base portion of the device. It will be observed that the upper surface of the tier 10 is indicated by the numeral 14 and that the same is at an elevation in respect to the face 11 of the tier 10A. The same is true of the upper surface 15 of the tier 10B and it will be observed that by referring to Figure 2 in particular that the openings are formed in the uppermost faces 11, 14 and 15 of the device. In order that bottles of liquor may be positioned in the openings and supported in a manner so that a majority of the surface area of the bottle is in view above the level of the uppermost faces 11, 14 and 15 of the device as the case may be, a plurality of cup-like holding members 12 are positioned, one in each of the openings, and by referring to Figure 4 of the drawing a cross sectional side elevation of one of these holding members 12 may be seen.

Each of the holding members 12 comprises an annular flange from which a circular sleeve 13 depends. A partial bottom 15 is provided and defines an opening 16 therein. A plurality of ribs 17 are positioned vertically about the interior surfaces of the holding members 12 and horizontal extensions 18 thereof continue on the uppermost surface of the bottom portion 15 of the holding member 12.

In Figure 4 a dotted line representation of a portion of a liquor bottle is indicated by the numeral 19 as being positioned in the holding member 12. It will be observed that the ribs 17 and 18 position the bottle 19 so that cold air introduced into the holding member 12 can readily flow around the bottom and outside surfaces of the bottle 19. A plurality of openings 20 are formed in the holding members 12 through the

depending sleeve portions 13 thereof. The cold air is introduced through the opening 16 and the openings 20. It will be observed that the annular ring-like opening defined by the exterior of the bottle 19 and the interior of the holding member 12 will create a jet-like effect upwardly around the sides of the bottle 19. It will further be observed that each of the holding members 12 are formed of a light transmitting material so that illumination means positioned within the interior of the device illustrated in Figures 1, 2 and 3 serves to illuminate the bottles positioned in the holding members 12 in a satisfactory manner so that the labels thereon as well as the bottles themselves may be readily identified.

In Figure 3 of the drawing, which is a cross sectional elevation on an enlarged scale, taken, in effect, on lines 3—3 of Figure 1, means for cooling the bottles positioned in the device may be seen as comprising an arrangement of cooling coils 21 which are formed in half-circular design so that cold radiated therefrom is directed against the holding members 12 and the bottles positioned therein.

In order that cold air may be moved upwardly through the openings defined about the exterior surfaces of the bottles 19 positioned in the holding members 12, a small, slow moving fan 22 is provided and is positioned adjacently to an opening 23 of moderate size formed in a back wall 24 of the device. Thus, air from the exterior of the device is moved slowly through the opening 23 by the fan 22 and upon being cooled by the cooling coils 21 which are in communication with a conventional compressor (not shown) is circulated through the interior of the device and upwardly through the passageway defined between the bottles held by the device and the holding members 12. In order that satisfactory illumination of the bottles positioned in the device may be provided, tubular lighting means of the low temperature type commonly known in the art is indicated by the numeral 25. It is obvious that as many of these light sources as may be required may be positioned within the device so that the illumination transmitted through the bottle positioning and holding members 12 will be adequate for the purpose.

The device of the invention is preferably formed of durable material such as either metal or wood, and the upper faces 11, 14 and 15 of the tiers 10, 10A and 10B are preferably provided with a surface of material which will be unaffected by the accidental depositing thereon of the liquid contents of the bottles positioned in the cooling and display stand. In Figures 3 and 4 this material is indicated by the numeral 26 and may comprise a section of stainless metal, a section of suitable linoleum or a section of a suitable plastic. The enlarged sectional elevation in Figure 4 shows the structural material of the device and the same is represented by the numeral 27. Insulation of a suitable character is illustrated by the numeral 28. In connection with Figure 3 of the drawing it will be

seen that the entire interior of the device is insulated and the insulation is preferably coated with waterproof substances to prevent decomposition thereof by moisture which is necessarily present due to the refrigerating coils 21 and their tendency to acquire frost from the moisture content of the air which is circulated through the device.

In Figures 3 and 5 of the drawing, a modification of the bottle holding member is illustrated, the modification comprising, as is best shown in Figure 5, a collar-like structure 29 formed of translucent material and provided with vertically extending ribs 30 for positioning the bottle therein. The collar member 29 serves only to position the bottle and to illuminate the same. A rack, preferably of wire, and placed in elevated relation to the base of the device is used as a base for the bottles and is positioned within the device by suitable means. Such a rack is shown in position beneath the face 11 of the lowermost tier 10A in Figure 3.

It will thus be seen that an attractive, practical and convenient cooling and display stand for bottled beverages such as liquors has been devised wherein the dual actions of cooling and illuminating are incorporated and in connection with which the device itself forms an ornamental article for positioning upon the back bar of a liquor serving establishment and so positions the bottles as to make them readily available to the bar-tender and at the same time readily visible to the patrons.

Having thus described my invention, what I claim is:

1. A cooling and display stand comprising a tiered structure having a plurality of surface levels, a plurality of openings formed in the said surface levels and means located beneath each of the said openings, in the structure, for supporting bottles partially positioned in the said openings, means located in each of the said openings and adapted to position the bottles therein, said means comprising a collar-like structure having an annular flange formed thereon and provided with vertically positioned rib structures in its inner surfaces so as to position the bottle and form an air passageway between the gasket-like structure and the bottle.
2. A cooling and display stand comprising a tiered structure having a plurality of surface levels and means located beneath each of the said openings, in the structure, for supporting bottles partially positioned in the said openings, means located in each of the said openings and adapted to position the bottles therein, said means comprising a collar-like structure having an annular flange formed thereon and provided with vertically positioned rib structures in its inner surfaces so as to position the bottle and form an air passageway between the gasket-like structure and the bottle, the said gasket-like structure formed of translucent light transmitting material.

MURRAY M. FIBUS.
